UNITED STATES PATENT OFFICE.

CHARLES E. TEST, OF INDIANAPOLIS, INDIANA, ASSIGNOR TO THE INDIANAPOLIS CHAIN AND STAMPING COMPANY, OF SAME PLACE.

DESIGN FOR A BICYCLE-CHAIN RIVET.

SPECIFICATION forming part of Design No. 27,066, dated May 18, 1897.

Application filed March 8, 1897. Serial No. 626,551. Term of patent 7 years.

To all whom it may concern:

Be it known that I, CHARLES E. TEST, a citizen of the United States, residing at Indianapolis, Marion county, in the State of Indiana, have invented and produced a new and original Design for Bicycle-Chain Rivets, of which the following is a specification, reference being had to the accompanying drawings, forming a part thereof.

Figure 1 is a plan view with one of the rounded angles of the body uppermost. Fig. 2 is an end view, and Fig. 3 is a cross-section on the line 3 3 in Fig. 1.

The leading feature of my design consists in a rivet having an extended body triangular in cross-section and cylindrical ends or necks. The triangular body is of about the same length as the ordinary cylindrical bod-

ies of this class of rivets and of uniform triangular section. The three faces of the triangular body are marked, respectively, 1 2 3. The angles are not sharp, but are rounded on a very small radius. The rounded angles are marked *a b c*. The cylindrical necks are marked D. They are of about the same length as the necks of ordinary rivets.

What I claim is—

The design for a bicycle-chain rivet herein shown and described.

In testimony that I claim the design above set forth I affix my signature in presence of two witnesses.

CHARLES E. TEST.
